Attorney

UNITED STATES PATENT OFFICE

GEORGE H. GILLIGAN, OF PROVIDENCE, RHODE ISLAND, ASSIGNOR TO U. S. RING TRAVELER COMPANY, OF PROVIDENCE, RHODE ISLAND, A CORPORATION OF RHODE ISLAND

TWISTER RING AND TRAVELER

Application filed August 12, 1931. Serial No. 556,524.

My invention relates to twister rings and cooperating travelers, both of the vertical type.

The essential objects of my invention are 5 to prevent excessive friction between the traveler and ring during the rotation of the former around the latter; to afford free delivery of the lubricant upon the ring face at all possible points of contact therewith by 10 the traveler; to enable the maintenance of the traveler in an upright or floating position relatively to the ring; to prevent lateral tipping of the traveler whereby gripping or binding of the latter upon the ring is often 15 induced; to afford a maximum of clearance for the filament engaged by the traveler; to maintain the traveler in a uniform horizontal plane throughout its rotation around the ring; and inexpensiveness of construction.

20 Other objects and advantages will be apparent to those familiar with the art and will be hereinafter adverted to.

My invention consists primarily in the means for accomplishing the above objects.

25 In the accompanying drawings which form a part of this specification,

Figure 1 is an isometric view of my ring and of my traveler mounted thereon,

Figure 2, an enlarged diametric section of 30 the ring showing the traveler in side elevation thereon engaging a thread, and

Figure 3, a fragmentary section of the ring supporting a modified form of my traveler.

35 Similar characters of reference indicate like parts throughout the views.

As herein shown my twister ring 4 includes an upright annular body 5 having transversely rounded upper and lower bearing edges 40 6 and 7, and provided with a transversely ar- cuate convex annular inner face 8 extending continuously from one bearing edge to the other.

A ring traveler 9 of the vertical type is slid- 45 ably mounted upon the ring. This traveler, formed from a flat oblong metallic strip, com- prises a substantially straight vertical shank 10; an upwardly and outwardly directed ar- cuate horn or foot 12 upon its lower end, and 50 an outwardly and downwardly directed horn

14 integral with the upper end of the shank.

At or adjacent the ends of the shank are interspaced horizontally disposed outwardly directed oblong bearing loops or projections 15 for impingement against the convex sur- face of the ring near the top and bottom of the latter, while the shank 10 at the apex 17 of the arc midway the loops 15 is adapted to contact with the center of the arc of the face 8.

55 In operation the thread 19 extending from the delivery rolls to the bobbin propels the traveler circularly upon the ring, with the foot 12 in more or less constant contact with the bearing edge 7. During this rotary travel the projections 15 of the traveler coop- erate with the convex face 8 of the ring to insure a minimum degree of frictional contact between the parts, tends to maintain the traveler in an upright, floating, or nontilted 60 position or in a uniform horizontal plane throughout its rotary course of travel, and insures ample clearance for the thread 19 to pass through the upper end of the traveler.

65 The convex form of the ring face 8 facil- itates the delivery thereover of any lubricant, if for any reason lubrication of the foot 12 or the projections 15 should be deemed neces- sary.

70 A modified form of my invention is shown in Figure 3 wherein one of the projections 15 is omitted.

75 It will be understood that any changes of detail of construction, within the scope of the language of the claims, is permissible with- out departing from the spirit of the inven- tior.

I claim:—

1. In a ring twisting device, a ring comprising a vertical annular body, the inner face of said body extending in a continuous and unobstructed convex arc from the top to the bottom of the body, and a traveler comprising a vertical shank within the ring, horns upon the shank extending outwardly beyond the top and bottom of the body, and an out- 80 wardly directed bearing member upon the shank engageable with the convex face of the body.
2. In a ring twisting device, a ring compris- 85

ing a vertical annular body, the inner face of said body extending in a continuous convex arc from the top to the bottom of the body, and a traveler comprising a vertical shank 5 within the ring, horns upon the ends of the shank, and looped bearing members upon the shank engageable with the convex face of the body.

3. In a ring twisting device, a ring comprising a vertical annular body, the inner face of said body extending in a continuous convex arc from the top to the bottom of the body, and a traveler comprising a vertical shank within the ring, horns upon 10 the ends of the shank, an intermediate portion of said shank being adapted to contact with the apex of the face, and a looped bearing member upon the shank spaced from said intermediate portion engageable with 15 the face.

4. In a ring twisting device, a ring comprising a vertical annular body, the inner face of said body extending in a continuous convex arc from the top to the bottom of the body, 20 and a traveler comprising a vertical shank adapted to contact intermediate its length with the convex face, horns upon the ends of the shank, and bearing members upon the shank between the horns and the contacting 25 portion of the shank engageable with the convex face.

5. In a ring twisting device, a ring comprising a vertical annular body, the inner face of said body extending in a continuous convex arc from the top to the bottom of the body, 30 and a traveler comprising a vertical shank, horns upon the ends of the shank, and horizontally disposed bearing members projecting from the shank engageable with the 35 convex face.

6. In a ring twisting device, a ring comprising a vertical annular body provided with a convex face, and a traveler comprising a vertical shank within the ring, horns upon 40 the ends of the shank, and an outwardly directed bearing member upon the shank engageable with the convex face of the body.

In testimony whereof I have affixed my signature.

50 GEORGE H. GILLIGAN.
